UNITED STATES PATENT OFFICE.

FRANKLIN F. KNOUS, OF HARTFORD, CONN., ASSIGNOR TO THE COLTS PATENT FIRE ARMS MANUFACTURING COMPANY, OF SAME PLACE.

MAGAZINE FIRE-ARM.

SPECIFICATION forming part of Letters Patent No. 358,279, dated February 22, 1867.

Application filed November 8, 1886. Serial No. 218,274. (No model.)

To all whom it may concern:

Be it known that I, FRANKLIN F. KNOUS, of Hartford, in the county of Hartford and State of Connecticut, have invented a new Improvement in Magazine Fire-Arms; and I do hereby declare the following, when taken in connection with accompanying drawings, and the letters of reference marked thereon, to be a full, clear, and exact description of the same, and which said drawings constitute part of this specification, and represent, in—

Figure 1, a sectional side view showing the parts in the closed position; Fig. 2, a sectional view of so much of the arm as illustrates the locking-lever, slide, and hammer in the position of the breech-piece open; Fig. 3, a modification.

This invention relates to an improvement in that class of magazine fire-arms in which the mechanism of the arm is operated by means of a handle arranged beneath the barrel to be moved longitudinally backward and forward, and with a slide extending therefrom into the receiver to engage the operative mechanism of the arm, and so that as the handle is moved rearward the breech-piece is opened and the hammer thrown to full-cock, and on the return the breech-piece is closed, the invention being an improvement on the arm for which Letters Patent of the United States, No. 285,020, were granted to W. H. Elliot, September 18, 1883. In the said invention of Elliot a lever (called in the patent a "feed-pawl") is arranged beneath the slide, which extends from the handle, and hung upon a fulcrum, one arm extending forward and turned upward at its forward end, so as to serve as a stop for the column of cartridges in the magazine, under certain circumstances, to prevent the column from moving rearward. The other arm extends rearward, and is constructed with a shoulder or hook to engage a shoulder or stud on the hammer when the hammer is thrown to full-cock. In the operation of this lever, when the handle is in the extreme forward position the forward end of the lever or feed-pawl is depressed and out of the path of the column of cartridges. The rear end at the same time is raised, so as to leave the hammer free to be thrown forward

against the firing-pin; but as the hammer and the slide it carries move rearward the forward end of the said lever is permitted to rise and the rear end to descend under the action of a spring, and so that as the hammer approaches its extreme cocked position the shoulder or stud thereon will be engaged by the hooked end of said lever. At the same time the forward end of the said lever has been thrown upward to come in rear of the column of cartridges in the magazine to prevent a rear movement of that column. Then, as the handle is returned, taking with it the slide, and just as the breech-piece approaches its closed position, the slide strikes upon a cam-like surface near the forward end of the said lever and depresses that forward end of the lever, consequently raising the rear end and releasing the hammer, so that this lever serves the double purpose of a stop for the column of cartridges and as a lock to hold the hammer in its cocked position until the breech-piece shall be fully closed.

A difficulty arises in the use of this lever, from the fact that the stud or shoulder on the hammer passes to the rear of the extreme end of the lever in the action of the hammer; and, from the fact that this shoulder or stud may so escape entirely from the lever, it sometimes occurs that in cocking the hammer by hand the rear end of the lever will interfere with the cocking movement of the hammer, or the stud on the hammer is liable to pass above the rear end of the lever, and thus interrupt the proper working of the parts. Again, in the patent of Elliot the slide and handle are free for movement without other obstruction than the natural friction of the parts—that is to say, no device is provided to secure the handle with its slide in the extreme forward or breech-closed position; hence there is a liability of accidental partial rear movement of the handle and its slide and consequent release of the breech-piece.

The object of my present invention is to overcome these difficulties, and provide a locking device to temporarily hold the slide with its handle in the extreme forward position; and it consists in constructing the before-mentioned lever with an extension from the hook

or shoulder rearward and above the stud or shoulder on the hammer, with which the hook engages, the said rear extension being of such an extent that the stud or shoulder on the hammer cannot pass from beneath the said rear end of the lever, combined with an upward projection on the forward end of the lever, inclined upon its forward side, the said slide constructed with a recess upon its under side, with which the said projection on the lever may engage, and whereby the said engagement between the said lever and the said slide, under the action of the lever-spring, will serve to hold the slide and its handle forward in the closed position, yet yield to the forcible rear movement of the handle and slide, and as more fully hereinafter described.

In Fig. 1 I show the magazine, barrel, breech-piece, and its locking mechanism substantially the same as in the Elliot patent, before referred to, but not necessary to be particularly described, as it constitutes no part of my present invention.

A represents the handle, which is arranged forward of the receiver and slides parallel to the magazine in the usual manner for this class of arms. From the handle the bar or slide B extends rearward into the receiver, and so as to engage with the operative parts of the breech-piece in the usual manner.

C is the lever arranged below the slide B, and hung upon a fulcrum, a. At the forward end the lever terminates in an upward projection, b, to serve as the dog for the feed, the same as in the Elliot patent. The lever extends to the rear from the fulcrum, and near its rear end is constructed with a shoulder or hook, d, as in the Elliot patent, which is adapted to engage a stud or shoulder, e, on the hammer when the hammer is in the cocked position, as seen in Fig. 2. From the shoulder or hook d the lever extends rearward to a point beyond the extreme rear position at which the shoulder e stands when the hammer is in the closed position, as seen in Fig. 1; hence it is impossible that the stud or shoulder of the hammer can pass to the rear of the end of the lever C, so as by any possibility to interfere with the proper working of the parts, as in the Elliot patent. Again, the extension permits that end of the lever, when free, to come to a bearing upon the stud or shoulder e and rest thereon, so that as the hammer passes from the closed to the full-cocked position it will support that end of the lever until it reaches the notch d. Then under the action of the lever-spring D the rear end of the lever will be thrown downward to engage the shoulder or stud on the hammer, as seen in Fig. 2.

Near the forward end of the lever is an upward projection, f, inclined rearward and upward upon its forward side, and preferably upward and forward upon its rear side, and in the under side of the slide B and at a point corresponding to the upward projection, f, when the breech-piece is in the extreme closed

position, is a cavity, g, into which the projection f on the lever C may enter under the action of the spring D, and so that as the slide moves forward, say, from the position seen in Fig. 2 it will pass over the projection f on the lever until, in the extreme closed position, the cavity g in the under side of the lever presents itself to the projection f. Then the projection enters that cavity and offers a resistance to the rear movement of the handle and the slide B; but because of the incline of the forward side of the projection f the resistance is not so great as to materially interfere with the forcible rear movement of the handle and slide, so that the handle and slide are held in the extreme forward or closed position so firmly as to prevent accidental rear movement, but not sufficiently to interfere with intentional or practical rear movement of the handle and slide.

When the parts are in the closed position, as seen in Fig. 1, the slide B holds the forward end of the lever C so far downward that the extension of the rear end stands above or out of the path of the stud or shoulder e, as seen in Fig. 1; but after the slide starts in its rear movement it escapes from the projection f, as seen in Fig. 2, and so as to leave the forward end free to rise to a higher point, and consequently permit a further depression at the rear end; hence as the hammer arrives at the full-cock position the lever is free to drop at its rear end, to bring the shoulder d into engagement with the stud e, as seen in Fig. 2, this engagement being substantially the same as in the Elliot patent, and so that the hammer will be held in the cocked position until in the forward movement of the slide the lever will be again turned, so as to raise the shoulder d from engagement with the stud e.

The slide B is slotted forward of the cavity g, to permit the projection b and the forward end of the lever to work up through the slide, and preferably the rear end of the slot—that is, immediately forward of the cavity g—is inclined downward and backward, to produce an easy cam-like action between the slide and the forward end of the lever in the final closing movement of the slide and handle.

While designed with special reference to magazine fire-arms, it will be evident to those skilled in the art that the lever to interlock the hammer and the handle may be employed in single breech-loaders, in which case the upward projection b at the forward end will be omitted.

While I prefer to make the engagement between the projection f and the slide by means of a cavity, g, formed in the under side of the slide, that cavity may be simply a shoulder or recess such as to present a shoulder to the forward side of the projection f only, as seen in Fig. 3.

I claim—

In a fire-arm in which the barrel opens into the receiver at the rear, and in which the breech-piece is arranged in rear of the barrel,

the hammer hung in the receiver in rear of the breech-piece, and in which the breech-piece is operated by a longitudinally-reciprocating handle forward of the receiver, with a slide 5 connecting said handle and the operative mechanism of the breech-piece, the combination therewith of a lever hung upon a fulcrum in the receiver below the said slide, one arm of said lever extending forward beneath said 10 slide, and at its forward end constructed with an upward projection, having its forward surface inclined upward and backward, the said slide constructed with a shoulder corresponding to the forward side of said projection on 15 the lever when the breech-piece and slide are in the closed position, the said projection adapted to engage said shoulder on the slide, the other arm of the said lever extending to

the rear, constructed with a hook or shoulder, *d*, upon its under side and with an extension 20 therefrom rearward, the hammer constructed with a stud or shoulder arranged to work beneath the said rear extension of the lever and adapted to engage the said hook or shoulder *d* of said lever when the hammer is in the extreme 25 cocked position and the said lever free from engagement with the slide, the said extension from the hook rearward being to a point beyond the extreme rear movement of the said stud or shoulder on the hammer, substantially as described. 30

FRANKLIN F. KNOUS.
